(57) **CLAIM**

The ornamental design of a septic chamber body as shown and described.

DESCRIPTION

FIG. 1 is a front perspective view of a septic chamber body showing my new design;

FIG. 2 is a bottom perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a front elevational view thereof.

The uneven broken lines define the outer boundaries of the claimed design and form no part of the claimed design. Other evenly broken lines illustrate portions of the septic chamber body that form no part of the claimed design. Additional broken lines toward the center of the septic chamber body show a symbolic break in length where the appearance of any portion of the septic chamber body between these break lines forms no part of the claimed design.
